UNITED STATES PATENT OFFICE.

ELMER J. BRYANT, OF WOONSOCKET, RHODE ISLAND, ASSIGNOR TO THE TAFT-PEIRCE MANUFACTURING COMPANY, OF WOONSOCKET, RHODE ISLAND, A CORPORATION OF RHODE ISLAND.

DESIGN FOR A UNIVERSAL RIGHT-ANGLE IRON.

51,581.

Specification for Design.

Patented Dec. 18, 1917.

Application filed January 8, 1915. Serial No. 1,252. Term of patent 14 years.

To all whom it may concern:

Be it known that I, ELMER J. BRYANT, a citizen of the United States, a resident of Woonsocket, in the county of Providence, State of Rhode Island, have invented a new, original, and ornamental Design for a Universal Right-Angle Iron, of which the following is a specification, reference being had to the accompanying drawings, forming a part thereof.

Figure 1 illustrates a side elevational view of my design. Fig. 2 illustrates a back elevational view of my design. Fig. 3 illustrates a perspective view of my design.

The design illustrated in this case is intended to disclose a universal right angle iron wherein all exterior surfaces lie in planes, which when projected upon an intersecting right angle plane, form right angle rectangular figures.

I claim:—

The ornamental design for a universal right angle iron, as shown and described.

ELMER J. BRYANT.
